Primary Examiner — Cynthia Ramirez*Assistant Examiner* — L. Martinez(74) *Attorney, Agent, or Firm* — Yuri Chumak(57) **CLAIM**

The ornamental design for a wrap, as shown and described.

DESCRIPTION

FIG. 1 is a perspective view of a first embodiment of a wrap, showing our new design in a configuration of use;

FIG. 2 is a front elevation of a second embodiment of the wrap, showing our new design;

FIG. 3 is a rear elevation view thereof;

FIG. 4 is a left side view thereof;

FIG. 5 is a right side view thereof;

FIG. 6 is a bottom plan view thereof;

FIG. 7 is a top plan view thereof;

FIG. 8 is a perspective view of a third embodiment of the wrap, showing our new design;

FIG. 9 is a front elevation of a fourth embodiment of the wrap, showing our new design;

FIG. 10 is a rear elevation view thereof;

FIG. 11 is a left side view thereof;

FIG. 12 is a right side view thereof;

FIG. 13 is a bottom plan view thereof; and,

FIG. 14 is a top plan view thereof.

The broken lines in the drawings illustrate environmental subject matter only and form no part of the claimed design. The wrap is shown with a symbolic break in its length. The appearance of any portion of the wrap between the break lines forms no part of the claimed design.
